(57) **CLAIM**

The ornamental design for a water pipe as shown and described.

DESCRIPTION

FIG. 1 is a top perspective view of a water pipe showing our new design.

FIG. 2 is a front view thereof.

FIG. 3 is a left view thereof.

FIG. 4 is a top view thereof.

FIG. 5 is a right view thereof.

FIG. 6 is a bottom view thereof; and,

FIG. 7 is a rear view thereof.

The oblique lines on the water pipe indicate that those surfaces are transparent. The broken lines in the drawings depict portions of the water pipe that form no part of the claimed design.
